(57) **CLAIM**

The ornamental design for a universal tool carrier, as shown and described.

DESCRIPTION

FIG. 1 is a perspective view of the universal tool carrier showing my new design;

FIG. 2 is a top view thereof;

FIG. 3 is a front view thereof;

FIG. 4 is a right side view thereof;

FIG. 5 is a back view thereof;

FIG. 6 is a left side view thereof;

FIG. 7 is a bottom view thereof; and,

FIG. 8 is a section view along line 8—8 of FIG. 1.

The broken line showing of handle and hinge details in FIGS. 1-8 is included for the purpose of illustrating portions of the universal tool carrier and forms no part of the claimed design.
